UNITED STATES PATENT OFFICE.

PERCY COLE, OF PIPESTONE, MINNESOTA.

BAG-HOLDER.

SPECIFICATION forming part of Letters Patent No. 296,135, dated April 1, 1884.

Application filed September 11, 1883. (No model.)

To all whom it may concern:

Be it known that I, PERCY COLE, of Pipestone, in the county of Pipestone and State of Minnesota, have invented a new and Improved Bag-Holder, of which the following is a full, clear, and exact description.

The object of my invention is to provide a new and improved device for holding a bag while the same is being filled.

10 This invention is an improvement on the bag-holder for which Letters Patent of the United States No. 174,485 were issued to me on the 7th day of March, 1876.

Reference is to be had to the accompanying drawings, forming part of this specification, in which similar letters of reference indicate corresponding parts in both the figures.

Figure 1 is a perspective view of my improved bag-holder. Fig. 2 is a perspective view of the upper part of the same, showing it holding a bag.

A standard, A, is provided at its lower end with a small pivoted wheel or roller, B, on which it rests. Two braces, C, project downward and outward from the standard, at about the middle of the same, the lower ends of the said braces being pointed. The standard A is provided with a series of apertures, a. Two upwardly-projecting rods, D, are united at the lower ends, and provided with a pin, E, adapted to be passed into the apertures a in the standard A. A U-shaped frame forms two arms, F, which are riveted to the rods D. The cross-piece of the U-shaped frame is bent to fit against the standard. From the arms F the rods D extend upward a short distance, and are then bent upward and outward, and have downwardly-projecting hooks D' formed on the ends, to hold them to the staples of hopper when 40 the latter is turned down into a working posi-

tion. The upper ends of the rods D pass through staples G on the outer surface of one side of a hopper, H, adapted to rest on the arms F. The hopper is provided at the bottom edges and at the outer end with two downwardly-projecting clips, J, which fit against the outer sides of the arms F. At the front the hopper is provided with a thumb-piece, K, which is used to draw the hopper forward. The arms F and the rods D can be adjusted 45 higher or lower, according to the height of the bag, the pin E being passed into one of the holes a, to hold the arms F at the desired height. If a bag is to be held, the hopper is swung up, as shown in Fig. 1, and the upper 50 edges of the bag M are folded over the arms F, and then the thumb-piece K is seized, and the hopper is drawn forward and then swung down. The clips J rest against the outer sides of the arms F, and thus hold the bag in place. The 55 material with which the bag is to be filled is passed into the hopper H.

Having thus fully described my invention, I claim as new and desire to secure by Letters Patent—

The combination, with the post A and a hopper having staples G, of two upwardly-extending rods, D D, having each a bend to form a rest for the hopper end, and an end hook, D', to catch on the staple, whereby the 60 hopper may be turned up, slid back, and caused to rest with its rear end upon the rods and the post, or drawn out to the end of said rods and turned down into a working position, as described.

PERCY COLE.
